UNITED STATES PATENT OFFICE

PAUL F. COX, OF CHICAGO, ILLINOIS, ASSIGNOR TO THE GOSS PRINTING PRESS COMPANY, OF CHICAGO, ILLINOIS, A CORPORATION OF ILLINOIS

SMUT REMOVER FOR TRAVELING-CYLINDER WEB-PRINTING PRESSES

Application filed February 13, 1929. Serial No. 339,597.

This invention is an improvement in flat bed web printing presses of the type shown in my Patent No. 988,548, dated April 4, 1911 and application (Case 7589) filed November 5 14, 1928, Ser. No. 319,242. The object of the present invention is to provide such a press with novel means for removing the smut caused by offset from the freshly printed paper upon the second impression cylinder, 10 or any cylinder that receives offset from the "perfected" side of a freshly printed web.

In the aforesaid type of presses the impression cylinders are reciprocated back and forth over the type beds or printing surfaces 15 to produce impressions upon the web, which is ordinarily led successively between the cylinders and beds, one side of the web being printed by the first cylinder and bed, and the other side printed by the second cylinder 20 and bed. The second or perfecting cylinder contacts with the freshly inked side of the web which has been printed by the first cylinder and bed and some of the ink adheres to the second impression cylinder and would 25 smudge the paper.

My present invention provides novel and efficient means for keeping the surface of the second or perfecting cylinder clean, by removing the offset ink or smudge therefrom 30 as hereinafter explained.

The accompanying drawings illustrate one practical embodiment of my invention as applied to a press in which the cylinders are "on impression" on one stroke—and are "thrown off impression" during their return stroke; I will explain the invention with reference to such drawings, and summarize in the claims the essentials of the invention, and the novel 40 features of construction and novel combinations of parts, for which protection is desired.

In the drawings:

Figure 1 is a detail diagrammatic side elevation of a press equipped with my novel

means for removing smudge from the perfecting impression cylinder.

Figure 2 is an enlarged end view of the upper cylinder and smut removing devices.

Figure 3 is a top plan view of the devices 50 shown in Figure 2.

In the drawings 1 and 1^a designate parallel type beds arranged one over the other in a suitable main frame. Respectively cooperating with these beds are traveling impression cylinders 2 and 2^a. These cylinders are mounted in bearings in crossheads 3, which are guided in longitudinal guide ways 4^x in the side frames of the press. The crossheads 3 may be reciprocated so as to move the cylinders 2 and 2^a back and forth over the beds 1 and 2 by any suitable means, preferably by means of pitmen 3^a connecting the crossheads with crank gears 4.

The cylinder 2 is shown as journaled in 65 eccentric bearings 5^a on the crosshead, and the cylinder 2^a in eccentric bearings 5^a on the crosshead which bearings are preferably constructed and operated as shown in my Patent No. 1,475,566 or in my aforesaid application.

In such presses the web *w* is usually led from a roll *W* under an idler guide *g* to a roll 15, a set of endless tapes 15^b cooperating with the roll 15 to infeed the web. From roll 15 the web *w* is led under a guide *g'* to a guide *g*²; and then to a looping roller 6^a. From roller 6^a, the web is led to a guide *g*³ mounted on the crossheads adjacent cylinder 2, then under cylinder 2 to and over a guide *g*⁴ on the crossheads beside cylinder 2; then to a guide *g*⁵ at the rear end of the frame and up over a guide *g*⁶ on the frame; thence inwardly to a guide *g*⁷ mounted on the crossheads adjacent cylinder 2^a; then under cylinder 2^a 80 and up over a guide *g*⁸ beside cylinder 2^a; then to and around a looping roller 6^b, then back under a guide *g*⁹; and to and over an adjustable tensioning roller *g*¹⁰; and to the delivery 90

roll 8 from which the web passes out to the folding and delivering devices not shown.

In the actual press the eccentrics are shifted by suitable means so as to throw and hold the cylinders "on impression" during one stroke and throw and hold them "off impression" during their return stroke, and while the cylinders are off impression the web is fed forward between the beds and cylinders. The general construction and arrangement of all the aforesaid parts are well known and fully explained in my aforesaid patent and application and needs no further detailed explanation herein.

The side of the web printed by the lower cylinder 2 and bed 1 comes into contact with the surface of the upper cylinder 2^a which rolls upon the freshly printed surface of the web while impressing it upon the forms on bed 1^a, and also while the web is shifted past such cylinder, and ink from the freshly printed web will offset upon and accumulate upon cylinder 2 and would ultimately smudge the web. In order to prevent this smudging I provide novel devices to remove the ink or smut from the surface of cylinder 2, as follows.

Attached to arms 3^a on the crossheads 3 and adjacent the cylinder 2^a is a transverse shaft 30 or rod 3^c upon which are castings 5 which extend toward and above the cylinder 2. Each casting 5 is provided with a bearing 5^a for the reception of the shaft 6^a of a cleaning roll 6, preferably of composition, which is 35 adapted to contact with the surface of cylinder 2^a when the latter is "off impression" (see Fig. 2). The contact pressure of roll 6 upon cylinder 2^a can be regulated by a stud 5^b attached to the crosshead and freely extending through a lug 5^c on the free end of member 5. Said casting being adjustably positioned by nuts 5^d on stud 5^b above and below the lug 5^c. A spring 5^e attached to the casting 5, projects into the slot 5^a as indicated 40 in Figs. 1 and 2, and serves to yieldingly retain the shaft 6^a of the roll in the bearing 5^a, but permits the roll to be readily removed and replaced.

A wiper 7 (preferably a roll covered with 50 felt or other suitable material that will remove the smut from the composition roll 6) is mounted beside roll 6. As shown the shaft 7^a of wiper roller 7 is mounted in holders 7^b adjustably secured to the member 5 by 55 means of bolts 7^c tapped through slots in the holders 7^b. This enables the roller 7 to be adjusted to or from the roll 6, and caused to contact therewith with any desired pressure. Suitable means are provided to prevent roller 60 7 being rotated by frictional contact with the roll 6. As shown a screw 7^d tapped into the holder 7 engages one of a series of notches 7^e in the shaft 7^a of the roller 7, and prevents roller 7 turning with the roll 6.

65 Roller 7 acts as a wiper for roll 6 and re-

moves the smut and ink therefrom. At intervals, varying according to the accumulation of smut or ink on the roller 7—the screw 7^d can be withdrawn and roller 7 partly turned to bring a fresh surface thereof into contact with roll 6, and then screw 7^d re-engaged with roller 7. Such adjustment of the roller 7 is only necessary when the wiping material at the point of contact with the roll 6 becomes so saturated with ink or smut that it will not properly clean the roll 6. Both roll 6 and roller 7 can be readily removed to permit packing the cylinder 2^a and for cleaning.

It should be noted that the roll 6 only contacts with cylinder 2^a during the non-impression stroke of the cylinder 2^a and while said cylinder is "thrown off impression". This is important because if the roll 6 was in contact with the cylinder 2^a on both strokes of the cylinder it would on one stroke of the cylinder take smut therefrom and, on the return stroke of the cylinder would re-deposit the smut on the cylinder. Due to the throwing off and throwing on of cylinder 2^a the roll 6 will remove offset ink from the cylinder 2^a while the latter is thrown on impression and printing: but when the cylinder 2^a is thrown off impression, and not printing (during which time the web is fed past the cylinder 95 without being held tightly thereagainst) the roll 6 is out of contact with the cylinder 2^a and consequently does not re-deposit ink thereon.

In some cases, for color printing—a narrow web is led between the lower and upper cylinders and beds, as above described, on one side of the press, and then is deflected to the other side of the press and again led a second time successively between the beds and cylinders. In such cases or where the web is led twice between the lower cylinder and bed the latter may also be provided with a smut removing device as above described.

I claim:

1. In a printing press having a bed and a traveling cylinder cooperating with the bed, and means for throwing the cylinder off impression on one stroke, smut removing devices adapted to clean the cylinder while it is thrown off impression.

2. In a machine as set forth in claim 1, said smut removing devices comprising a roll adapted to contact with the periphery of the cylinder when it is thrown off impression, and a wiper contacting the said roll.

3. In a web printing press having a bed and a traveling impression cylinder cooperating with the bed, means for leading a web between the bed and cylinder, and means for throwing the cylinder on and off impression, of smut removing devices adapted to cooperate with said cylinder only while it is thrown off impression.

4. In a machine as set forth in claim 3, said smut removing devices comprising a roll

adapted to contact with the periphery of the impression cylinder when it is thrown off impression, a relatively fixed wiper roller beside the roll, and means for rotatably adjusting and holding said wiper roller in contact with said roll.

5. In a web printing press having beds and reciprocating cylinders, cross heads for reciprocating the cylinders over the beds, and means whereby the cylinders are thrown off impression on one stroke and on impression on the return stroke; of smut removing devices mounted on the cross head and adapted to cooperate with the impression cylinder 10 only when the latter is off impression.

6. In a web printing press having stationary beds and reciprocating impression cylinders, cross heads for reciprocating the cylinders over the beds, means whereby the cylinders are held off impression on one stroke and held on impression on the return stroke; with smut removing devices mounted on the cross head and adapted to clean the perfecting impression cylinder while the latter is off impression.

7. In a web printing press having stationary beds and reciprocating cylinders, cross heads for reciprocating the cylinders over the beds, and means whereby the cylinders are held off impression on one stroke and on impression on the return stroke; smut removing devices comprising a composition roll adapted to contact with the periphery of the impression cylinder when it is thrown off impression, a relatively fixed non-rotatable table wiper roller mounted beside the composition roll, and means for rotatably adjusting and holding said wiper roll.

8. In a web printing press having beds and reciprocating cylinders, cross heads for reciprocating the cylinders over the beds and eccentrics for throwing the cylinders on and off impression, a cleaning roll mounted on said cross heads and adapted to contact with the upper impression cylinder when the latter is thrown off impression, a wiper roller mounted on the cross heads adjacent the composition roll, and means for adjusting the wiper roll relative to the roll.

50 9. In a web printing press having stationary beds and reciprocating cylinders, cross heads for reciprocating the cylinders over the beds and eccentrics for throwing the cylinders on and off impression; members pivoted on the cross heads, a cleaning roll mounted in said members and adapted to contact with the upper impression cylinder when the latter is thrown off impression, a wiper roller mounted on the members adjacent the cleaning roll, means for adjusting the wiper roll relative to the composition roll, and means preventing rotation of the wiper roller while in contact with the cleaning roll.

65 10. In a web printing press having a printing couple including an impression cylinder

and bed; means for leading a web between the bed and cylinder; and smut removing devices adapted to cooperate with said cylinder only while it is not in impression.

11. In a machine as set forth in claim 10, said smut removing devices comprising a roll adapted to contact with the periphery of the impression cylinder when it is not in impression, a relatively fixed wiper roller beside the roll, and means for rotatably adjusting and holding said wiper roller in contact with said roll.
